Dobson, N.C. 27017

Primary Examiner—Catherine E. Kemper
Attorney, Agent, or Firm—Mills & Coats

[**] Term: 14 Years

[57] CLAIM

[21] Appl. No.: 326,672

The ornamental design for a wood fueled water heater
or the like, as shown and described.

[22] Filed: Dec. 2, 1981

DESCRIPTION

[51] Int. Cl. ..... D23—97

FIG. 1 is a front perspective view of the wood fueled
water heater or the like showing my new design, the
side opposite that shown being substantially a mirror
image thereof;

[52] U.S. Cl. D23/86

FIG. 2 is a top plan view thereof;
FIG. 3 is a rear elevational view thereof;
FIG. 4 is a bottom plan view thereof.
